UNITED STATES PATENT OFFICE.

AGNES HAWKINS, OF DALLAS, TEXAS.

DETACHABLE, VENTILATED ADJUSTABLE HAT LINING.

Application filed April 16, 1927. Serial No. 184,273.

This invention relates to improvements in hats, but more particularly the object of the invention is to provide a new and improved hat lining for ladies', men's and children's 5 hats.

The new and improved hat lining is so constructed and arranged as to permit the wearer's head ample ventilation and in addition the lining is capable of being easily 10 removed or attached to the hat or cap in a neat and practical manner without sewing or stitching in the usual way. Further, the invention includes means for adjusting a hat or cap to different sizes of heads, the 15 adjusting means also capable of being attached or removed in a novel and expeditious way in the same manner that the lining is attached or detached to or from the hat or cap.

Having the above objects in view the invention will be clearly understood from a perusal of the following detailed description, taken in connection with the accompanying drawing and wherein:

Figure 1 represents an elevational view of a lady's hat stock or hat body the outer covering or trimming being removed and the view partly broken away showing the interior arrangement of the hat and lining.

Figure 2 is an elevational view of the hat lining removed from the hat.

Figures 3 and 4 are side elevational views of two forms of pins or fasteners employed in securing the lining to the hat.

Figure 5 is an elevational side view of a pad used in making adjustments of the hat to proper head size, Figure 6 being a cross-sectional view along the line 6-6 of Figure 5; and

Figure 7 is a partial vertical sectional view along the line 7-7 of Figure 1 and through one of the pins, illustrating the mode of attachment.

Proceeding in accordance with the drawings and wherein similar numerals designate the various parts of the invention, 1 denotes a hat body or hat stock, covering removed. The lining for the hat is shown at 2, made of cloth or any suitable material 45 and fits or follows the inside formation of the hat. This lining is perforated at 3, the perforations being in rows and running in any preferred direction, a line of perforations being disposed around the lower edge 50 of the lining as at 4, primarily for the purpose of enabling the pins 5 and 6 to be in-

serted through the perforations in attaching the lining to the hat. It will be observed that the pins 5 and 6 are of different formation, the pin shown in Figure 4 having the 60 prongs 7 farther apart. In attaching the lining to a hat or cap the pin shown in Figure 3 is used, it being intended for ordinary hat lining material constructed according to the invention. The pin shown in Figure 4 65 is preferably for lining of finer or more delicate material. It will also be noted that both forms of pin have one prong longer than the other and that both prongs of both the forms of pin have the prongs nearer the 70 point flattened. The points of the pins are of almost needle-like penetration. The purpose of constructing one prong of the pins longer than the other is for the purpose of enabling the pins to be more easily inserted 75 through the perforations and to enable the longer prong to act as a "feeler" or guide means in securing the lining to the hat at the base of the hat.

In Figure 5 is illustrated a pad of material similar to the hat lining material and including a line of perforations 9, and a line of perforations through the center at 10. This pad has a filler of cotton 11 or the like and is employed to be placed in a hat at the 80 back or front. This pad may be either between the hat and lining or occupy a position directly next the lining between the lining and the head of the wearer, its function being to reduce the size of the hat. This 85 pad is secured in position in the same manner as the lining—with the pins 5 and 6.

In attaching the lining to a hat or cap the lining is placed in the hat so as to lie snugly all around the interior thereof. The perforations in the lower edges of the lining and the hat are made to register and the longer prong of a pin 5 is inserted through two registering holes of the hat and lining. This is clearly shown in Figure 7. The longer prong 100 is inserted slightly in advance of the shorter prong on account of its longer length, the shorter prong being also inserted at practically the same time. After the prongs are passed through the hat and lining they are 105 then bent inwardly so as to again pierce the hat and then bent so that the points will lie between the lining and the hat as shown in Figures 1 and 7. In this manner the points of the pins are hidden and covered and the 110 lining is securely fastened. The lining, however, may be quite easily and quickly removed

and a new lining inserted by removing the pins. These pins are spaced apart an inch or so as required. In placing the lining in the hat if preferred and to give the fingers 5 freer movement, several of the perforations may be joined by cutting the small divisions therebetween.

The pad, reducer or adjuster is secured to the hat in the same manner as the lining and 10 may be placed either in between the lining and the hat or next the lining and the wearer's head, since the pins are easily removed.

The lining is adaptable to men's hats and 15 in such applications since men's hats are made of thick and close material, several perforations may be made in the hat beneath the outside band and the lining attached—the pins piercing the hat being covered by the band.

20 What is claimed is:

1. A ventilated lining for a hat, said hat having perforations adjacent to but spaced from the lower edge thereof, said lining having 25 a line of perforations extending completely around said lining adjacent to but spaced from the lower edge thereof, some of said last named perforations in said lining registering with said first named perfora-

tions of said hat, said perforations providing 30 ventilation and also means for attaching the lining to the hat, said lining being provided with additional perforations scattered throughout the surface thereof for providing ventilation through said lining, and a plurality of double-pointed pins cooperating with 35 said registered perforations for detachably holding said lining to said hat.

2. In structure of the class described, the combination with a hat body, of a lining detachably positioned therein and provided with a plurality of perforations throughout the surface and along the lower edge thereof, 40 said hat body being provided with perforations adapted to register with certain of said lining perforations, and double-pointed pins 45 for cooperating with said hat and lining perforations, said pins being inserted from the inside of the lining through said registering hat and lining perforations and projecting 50 to the outside of the hat and then being bent to project back through said hat with the points lying between said lining and said hat and bent at an angle to lie in the plane of the hat.

In testimony whereof I affix my signature.

AGNES HAWKINS.
